United States Patent Office

Des. 196,316
Patented Sept. 17, 1963

196,316

HANDLE FOR FRYPAN COVER OR THE LIKE

Robert O. Ernest, Oak Park, Ill., assignor to Sunbeam Corporation, Chicago, Ill., a corporation of Illinois

Filed May 29, 1963, Ser. No. 75,111

Term of patent 14 years

(Cl. D44—29)

FIG. 1.

FIG. 2.

FIG. 3.

FIG. 4.

FIG. 1 is a side elevational view of a handle for frypan cover or the like embodying my new design;

FIG. 2 is a top plan view thereof;

FIG. 3 is a front elevational view thereof; and
FIG. 4 is a rear elevational view thereof.

I claim:

The ornamental design for a handle for frypan cover or the like, as shown.
